UNITED STATES PATENT OFFICE.

ROY W. BIDDLECOM, OF LOS ANGELES, CALIFORNIA, ASSIGNEE TO L. B. GIRARD, OF LOS ANGELES, CALIFORNIA.

FABRIC-CLAMP.

1,351,551.

Specification of Letters Patent. Patented Aug. 31, 1920.

Application filed December 16, 1919. Serial No. 345,374.

To all whom it may concern:

Be it known that I, Roy W. BIDDLECOM, a citizen of the United States, residing at Los Angeles, in the county of Los Angeles and State of California, have invented a new and useful Fabric-Clamp, of which the following is a specification.

This invention relates to a device for holding fabric when the latter is stretched under tension.

An object of this invention is to provide a fabric clamp which will effect a tight and certain grip upon the edge of a fabric which grip will withstand without loosening an unlimited amount of pull upon the fabric.

Particularly my invention pertains to the provision of means for effectively securing the edges of tightly stretched fabric to the frame within which the fabric is stretched. For example, my invention is adapted for application to the fabric holding frames utilized in the manufacture of window shade cloth.

A further object of my invention is to provide a clamp of the character referred to which will be simple and rapid in operation.

Another object of my invention is to provide such a clamp which will be of few parts and nonexpensive in manufacture.

Further objects and advantages will appear from the subjoined detailed description.

The accompanying drawings illustrate the invention.

Figure 1 is a view illustrating a fabric secured to a frame member by means of my novel clamp.

Fig. 2 is a vertical section of the same taken on a line indicated by x^2-x^2 in Fig. 1.

Fig. 3 is a front elevation of one of the rectangular strip members included in my invention.

Fig. 4 is a front elevation of the other of said rectangular strips.

Referring to the drawings, 1 designates a frame member which may be of any desired type utilized in the art.

Preferably secured to the frame member 1 by means of screws 2 is a rectangular metal strip 3. The strip 3 is bent or shaped along one longitudinal edge as at 4 and is doubled back as at 5 to form a groove 6, the longitudinal edge thereof being spaced from the strip 3. In practice the longitudinal extension 4 preferably projects from the body of

the strip 3 at an angle slightly more acute than a right angle and the extension 5 is doubled back to extend substantially parallel with the extension 4.

A second rectangular metal strip 7 is provided along one longitudinal edge with a tongue 8 which tongue projects therefrom at an acute angle. The strips 3 and 7 are separable and are interfitted in the manner hereinafter described.

In practice, a fabric 9 is placed over the longitudinal edge of the strip 3 shaped to form the groove 6, with sufficient of the fabric to extend along a portion of the body of the said strip. The tongue 8 of the strip 7 is then interfitted over said fabric and within the groove 6 during which operation the body of the strip 7 will reach a position substantially perpendicular to the body of the strip 3, and the fabric will be pushed within the groove 6.

The body of the strip 7 is then revolved toward the body of the strip 3 until the opposed flat faces of said strips are closely adjacent and substantially parallel each other, as illustrated in Fig. 2. During such movement of the strip 7 the apex of the angle formed by the body of the strip 7 and the tongue 8 will act as a fulcrum and will be pivoted within the apex of the angle formed by the body of the strip 3 and the extension 4. The fabric 9 will thus be gripped between such fulcrum and the line upon which it pivots. Furthermore, when the strip 7 has reached the position indicated, the extreme longitudinal edge of the tongue 8 will bind the fabric 9 to the doubled back extension 5 providing a second line of grip for the same.

In practice I find it convenient to provide latching means to secure the strip 7 in clamping position and insure against accidental displacement of the same due to jolting or other causes. In fact, however, such latching means is not absolutely necessary as the tension upon the fabric 9 when it is stretched will have a tendency to tighten the grip of the tongue and groove arrangement by pulling upon the longitudinal edge of the lip 8 and will therefore cause the body of the strip 7 to remain adjacent the body of the strip 3 as desired. In the drawings a preferred form of latching means is indicated as comprising levers 10 pivoted at 11 to the frame member 1.

I have found that the fabric clamp com-

prising my invention will grip a fabric so securely that an unlimited strain may be placed upon the fabric without there resulting the slightest slipping of the same within the clamp. Furthermore, the absolute simplicity of my fabric clamp both in operation and construction is a wide advance over and departure from everything prior in the art.

10 My invention is not limited to any particular proportions or form of parts, but is of the scope set forth in the following claims.

I claim:

15 1. A fabric clamp comprising a strip having one longitudinal edge bent and doubled back to form a groove and a second strip having one longitudinal edge bent to form an angular tongue, said tongue interfitting within said groove to grip a fabric interposed between said strips.

20 2. A fabric clamp comprising a fixed strip having one longitudinal edge bent and doubled back to form a groove, and a detachable strip having one longitudinal edge bent at an acute angle to form a tongue, said tongue interfitting within said groove and

contacting with said fixed strip at the longitudinal edge of said tongue and at the apex of the angle formed at the juncture of said 30 detachable strip and said tongue to grip a fabric interposed between said strips.

3. A fabric clamp comprising a pair of strips having edges shaped to form a longitudinally extending tongue and groove 35 adapted to grip a fabric interposed therein when said tongue is interfitted within said groove and said strips are positioned with their flat meeting faces adjacent and substantially parallel each other.

4. A fabric clamp comprising a pair of strips having edges shaped to form a longitudinally extending tongue and groove, the tongue contacting at two points within the groove to grip a fabric interposed therein, 45 and means to secure said strips with their flat meeting faces adjacent and substantially parallel each other.

Signed at Los Angeles, California, this 5th day of December, 1919.

ROY W. BIDDLECOM.
